UNITED STATES PATENT OFFICE.

FRANK H. CHAPMAN AND OWEN E. KENNEY, OF TOLEDO, OHIO, ASSIGNORS TO THE YOST ELECTRIC MANUFACTURING COMPANY, OF TOLEDO, OHIO, A CORPORATION OF OHIO.

PULL-CHAIN GUIDE FOR ELECTRICAL SOCKETS.

1,200,168.

Specification of Letters Patent.

Patented Oct. 3, 1916.

Application filed December 10, 1915. Serial No. 66,165.

To all whom it may concern:

Be it known that we, FRANK H. CHAPMAN and OWEN E. KENNEY, citizens of the United States, and residents of Toledo, in the county of Lucas and State of Ohio, have invented a certain new and useful Pull-Chain Guide for Electrical Sockets; and we do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to electrical pull sockets and particularly to the pull chain guides therefor.

The object of our invention is the provision of improved means for attaching chain guides to pull sockets, whereby such guides can be secured to or removed from the socket parts in a simple, easy, and quick manner, thus enhancing the practicability and commercial value of devices of this character.

The invention is fully described in the following specification and while in its broader aspect it is capable of embodiment in numerous forms a preferred and a slightly modified form of the invention are illustrated in the accompanying drawings in which,

Figure 1 is a side elevation of a socket embodying the invention. Fig. 2 is a similar enlarged view thereof with parts broken away. Fig. 3 is an enlarged side elevation of the switch-containing insulating-body of the socket. Fig. 4 is a perspective view of the chain guide embodying the invention, and Fig. 5 is a similar view of a slightly modified form of the chain guide.

Referring to the drawings, 1 and 2 designate the base and cap members of the shell of an electrical socket, which may be separably secured together in any suitable or convenient manner, as is understood in the art, and 3 and 4 designate the base and cap members, respectively of the customary in-

terior insulating body of the socket. The 50 insulating members 3 and 4 coöperate to form an interior chamber 5 in which a switch of the pull chain type is disposed, and are separably secured together in any suitable manner. The means illustrated for 55 separately connecting the members 3 and 4 comprises two sets of interengaging spring contact fingers 6, with one finger of each set secured to and projecting from the base 3 and with the other fingers secured to and 60 projecting from the cap 4.

The pull chain 7 for the switch attaches in the present instance to the movable member 8 of the switch, which member registers with or projects into an opening 9 into the 65 side wall of the switch chamber 5, which opening preferably extends out on one side of the inner end of the insulated member 3.

10 designates an insulating lining that is disposed between the shell base 1 and the 70 insulating body 3, 4, as is customary in sockets of this type. The shell base 1 and insulating lining 10 are provided outwardly from their inner ends with registering slots or openings, as shown at 11, said openings 75 being capable of registering with the opening 9 in the insulating member 3.

The chain guide 12 is preferably of tubular form with its outer end outwardly flared, and is adapted to project through the openings 11 in the shell member 1 and insulating lining 10. The inner end of the guide 12 is provided with a laterally extending flange or enlargement 13, which is intended to rest against the side of the insulating member 3 at the margin of the opening 9. The edge of the flange or enlargement 13, which is disposed adjacent to the inner end of the insulating member 3, is provided with a tongue 14, which projects outwardly therefrom 80 lengthwise of the chain-guide and is intended to project between the adjacent edges of the insulating base and cap members 3, 4 within a recess 15 provided therefor, in the present instance, in the edge of the member 3, as shown in Figs. 2 and 3. The recess 15 in which the tongue 14 seats is approximately equal in depth to the thickness of the 85 90 95

tongue so that the insulating members 3 and 4, when secured together, have holding or clamping engagement with the tongue. The recess 15 is also substantially equal in width to the width of the tongue 14 so that the side walls of the recess co-act with the side edges of the tongue to prevent transverse shifting movements of the tongue and chain guide with respect to the insulating body.

It is preferable to transversely angle the free end portion of the tongue 14, as shown at 16 in Figs. 2 and 4, so that the tongue may have hooked retaining engagement with the interior of the insulating body, as indicated in Fig. 2, thus preventing a withdrawal of the tongue from between the insulating members 3, 4 until such members have been separated from their assembled positions. It will be understood, however, that the lip 16 at the end of the tongue 14 may be eliminated if desired, as shown in Fig. 5, as the chain guide is prevented from being outwardly withdrawn from the insulating body by the shell when the insulating body is disposed therein.

It is evident that we have provided simple means for easily and quickly attaching the chain-guide to an electrical socket without the use of screws or other securing means apart from the members of the insulation switch carrying body 3, 4.

We wish it understood that our invention is not limited to any specific construction, arrangement or form of the parts, as it is capable of numerous modifications without departing from the spirit of the claims.

Having thus described our invention what we claim is new and desire to secure by Letters Patent is,—

1. In an electrical socket, an insulating body having separable base and cap portions provided with a recess between the adjacent edges thereof, and a chain guide having an enlargement at its inner end for resting flat against the outer side of said body-adjacent to the outer end of said recess, and said enlargement having a tongue projecting at a right angle therefrom transversely of the insulating body and fitting in said recess, said tongue co-operating with the walls of said recess to prevent all except endwise movements of the tongue when the body parts are in assembled relation.

2. In an electrical socket, an insulating body having separable base and cap portions provided with a recess between the adjacent edges thereof and opening at its inner end into the interior of the body, and a chain guide projecting outwardly from said body and having an enlargement at its inner end which bears flat against the outer side of said body adjacent to said recess and having a tongue projecting at right

angles from said enlargement and hooked at its inner end, said tongue being adapted to seat in and project through said recess and to have its hooked end engage around a portion of the insulating body at the inner end of said recess, whereby the chain guide is held to the insulating body when the base and cap portions thereof are in assembled relation.

3. In an electrical socket, an insulating body having separable base and cap portions, the base portion having a pull chain opening in a side wall thereof and recessed in marginal relation to the outer end of said opening, with the inner end of the recess continuing over the inner end of said base portion and into the interior thereof, and a chain guide for projecting from the base portion of said insulating body, with its passage in communication with said opening, said guide having its inner end flanged and seating in said recess at the outer end of said opening and having a tongue projecting at an angle from one edge thereof and seating in the inwardly projecting portion of said recess over the inner end of the base portion with its inner end angled to have hooked engagement with the base portion at the inner end of said recess, said base and cap portions, when in assembled relation, coacting with said tongue and angled end thereof to retain the guide in engagement with the insulating body.

4. In an electrical socket, an insulating body having separable base and cap portions provided with a recess between the adjacent edges thereof, and a chain guide projecting outwardly from said insulating body and having a tongue projecting longitudinally from its inner end into said recess and angled to co-act with the insulating body to retain the chain-guide in engagement with the body when the parts of said body are in assembled position.

5. In an electrical socket, an insulating body having separably connected base and cap portions the base portion having an opening in its side wall and having its inner end recessed adjacent to said opening, and a chain guide projecting from said body in register with said opening and having its inner end flanged to rest against said body at the margin of its opening and providing a tongue for projecting into said socket, said tongue being prevented from movements lengthwise of the socket by the parts of the body secured together and being prevented from movements transversely of the socket by the end walls of said recess.

6. In an electrical socket, an insulating body provided in a side thereof with a transversely extending recess, a chain guide having an enlargement at its inner end for resting against the outer side portion of

said body adjacent to said recess, said enlargement having a tongue projecting therefrom transversely of the insulating body and fitting into said recess, said tongue co-operating with the walls of said recess to prevent all except endwise movements of the tongue, and an inclosing shell for the

insulating body coöperating to retain the chain guide to said body.

In testimony whereof, we have hereunto signed our names to this specification.

FRANK H. CHAPMAN.
OWEN E. KENNEY.
